Attorney

and further applications of the present invention. Accordingly, it is the object of the present invention to provide a novel tool for punching holes in brittle materials, such as balsa wood, or the like, which is economical to manufacture, rugged and efficient in operation.

Another object is to provide a novel punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Other objects and advantages of the present invention will appear more fully from the following description when considered together with the accompanying drawing, wherein:

Figure 1 is a perspective view of the present invention.

Figure 2 is a side view of the device.

Figure 3 is a top view of the device.

Figure 4 is a longitudinal cross section view of the same.

Referring in detail to the drawing and first with reference to Figure 4, the device comprises a pair of crossed handles 10 and 11 having integrally formed jaw members 12 and 13. The handles are pivoted on a rivet 15.

The jaw member 12 comprises a flat T-head having an elongated plate 16 with a centrally disposed rectangular punch receiving opening 17 therein; and the jaw 13 is a more conventional

lateral jaw member of a deeper profile than the jaw 12, having a flat top surface and a central longitudinal slot 18 extending therethrough. A pair of side flanges 19 are formed on the top surface of the jaw 13, one on each side of the slot 18, and a central longitudinal slot 20 is formed in the top surface of the jaw 12, one on each side of the slot 17.

Figure 5 is a longitudinal cross section view of the device showing the jaws 12 and 13 in a closed position.

BALSA PUNCH

David F. Brittle, Weaverville, N. C.

Application August 13, 1946, Serial No. 690,090

3 Claims. (Cl. 164—121)

1

The present invention relates generally to tools and more particularly to a tool for punching holes in brittle materials, such as balsa wood or the like.

One example of use for the present hole punching tool is in connection with the building of model airplanes. In making model airplanes from soft woods, such as balsa, a problem arises when it becomes necessary to punch holes in the wood. Model plane builders now usually laboriously cut holes by hand with a razor blade, making several cuts per hole to avoid splintering the wood. In some instances punches have been attempted to be used, but because most of the holes required in balsa bulkheads and formers in model airplanes are at the edge of the material, splintering action results from the use of a punch, such as the known ticket-type.

It is the primary object of the present invention to provide a novel tool for punching holes, whereby the punch element is arranged to cooperate with a pair of members adapted to maintain the material being worked on in a level plane and compressed substantially at right angles to the punch during punching to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Another object is to provide in a punch having a pair of cross-pivoted handles with jaw members continuing as an integral part thereof, a third and intermediate plate-like jaw with an opening for the punch element to work through for clamping and maintaining the material flat during the punching operation to avoid splintering.

Referring in detail to the drawing and first with reference to Figure 4, the device comprises a pair of crossed handles 10 and 11 having integrally formed jaw members 12 and 13. The handles are pivoted on a rivet 15.

The jaw member 12 comprises a flat T-head having an elongated plate 16 with a centrally disposed rectangular punch receiving opening 17 therein; and the jaw 13 is a more conventional

design and carries the punch element 19, which is preferably rectangular in cross-section. In forming the jaw 12 the same is made T-shaped, i. e., a relatively narrow flat section 20, forms the leg of the T, see Fig. 3. The leg 20 continues from the mid-side edge of plate 16. This leg section 20 has side flanges 21, which continue therefrom to merge into the handle 11. In the narrow flat leg section 20 is an opening 10 through which extends the end of an elongated rivet 22. The rivet 22 is upset on the end to limit the separatory movement of the jaws 12 and 13 and serves as a guide for these jaws and a third intermediate flat T-shaped jaw 24 having an elongated plate 25 similar in shape to plate 16 carried by jaw 12, as well as a flat leg section with an opening aligned with the opening in section 20 for rivet 22. The rivet 22 likewise serves as a mount for a spring 26. This spring 26 is coiled around the rivet 22 between the punch jaw 13 and the third jaw 24, and tends to expand, so as to normally raise the jaw 24 above the punch element 19 and yieldingly urge it toward the jaw 12 and its plate 16.

The intermediate T-shaped jaw 24 has a centrally disposed rectangular punch receiving opening 28, in the plate 25, in alignment with a similar opening 17 in the plate 16. Each of the plates 16 and 25 has its length extending trans-

30 verse the jaw members, and the jaw members 12 and 24, as mentioned above, are guided by rivet 22 and urged toward each other by the spring 26.

The leg 29 of jaw 24 continues from plate 25 and is curled around the shank of the rivet 15, which rivet is exposed through cut out portions of the handles back of the jaws 12 and 13.

In order to maintain the punch member 19

removed from the openings 17 and 28 in the plates 16 and 25, there is mounted between the handles 10 and 11 a wire spring 30. This spring

comprises a piece of resilient spring wire of V-shape with a spring coil 31 at the apex thereof and a finger-loop 32 at the end of one leg of the V. The coil 31 serves to spread the handles 40 apart and likewise the jaws 12 and 13, until the handles are squeezed together during the punching operation.

Operation

50 The device is used by the operator grasping the handles and squeezing them together in the same manner as any other punch. However, the resulting movement of the parts is novel, for example, the plates 16 and 24 are placed over the material to be punched. Regardless of the thick-

ness, assuming of course it is within the normal range of the jaw spread, the plates will yieldably apply some compressive stress on the material and keep it level and flat with respect to the punch member 19. As the handles are squeezed this yieldable application of compressive stress is increased, until the punch finally penetrates the material, whereupon the squeeze on the handles is released and the spring 30 returns the jaws to their respective normal positions.

Thus I have provided a novel hole puncher for materials likely to splinter, which gradually compresses the material and holds it level and flat with respect to the punch member after a reasonable degree of compression, until after the hole is punched, so as to prevent splintering of the material. While I have specifically referred to using this device for punching holes in balsa wood for making model airplanes, it is to be understood that many other uses may as well be made of the same. Also other embodiments of this device, which may now occur to others skilled in the art, are likewise intended to be covered hereby and reference should be had to the appended claims to determine the scope of the present invention.

What I claim is:

1. A punch tool comprising a pair of cross-pivoted handles, a jaw carried by the forward extremity of one handle, a punch pin secured to the jaw, a second jaw carried by the forward extremity of the other handle, the second jaw being in the form of a flat plate having a width materially greater than the width of the handles and of the first jaw, an intermediate jaw of substantially the same width as the second jaw, said intermediate jaw having a relatively long tail piece extended rearwardly and pivotally connected with the handles to turn on the pivotal center for the handles, the second and intermediate jaws having aligned openings to receive the punch pin, a rivet secured at one end to the first jaw at a point rearwardly from the punch pin, the second and intermediate jaws having aligned openings through which the rivet loosely extends, means upon the other end of the rivet for limiting the separatory movement of the first and second jaws, and a spring encircling the rivet and interposed between the first jaw and the intermediate jaw.

2. A punch tool of the character described in claim 1, wherein the first mentioned aligned openings of the second and intermediate jaws are of polygonal outline and said punch pin is of polygonal cross sectional form to conform to the outline of the said openings of the second and intermediate jaws.
3. A punch tool comprising a pair of handle members each having a forward end portion formed to provide spaced sides, the forward end portion of one handle being disposed between and in crossed relation with the sides of the forward end portion of the other handle, a pivot pin extending through the crossed portions of the handles, the forward extremity of the forward end portion of one handle having the sides thereof bridged by an intermediate plate forming a relatively narrow jaw, a wide jaw plate disposed across the forward extremity of the forward end portion of the other handle and having a rearwardly extending portion secured between the sides of the said other handle, a wide intermediate jaw plate of substantially the same form as the first wide jaw plate and in opposed relation therewith, said intermediate jaw plate having a central rearwardly extending tail portion terminating in an eye through which said pivot pin extends whereby the intermediate jaw plate swings on the pivot pin, said wide jaw plates having aligned openings, a punch pin carried by the first jaw and adapted to extend through the aligned openings, a rivet secured at one end to the first jaw and extending through aligned openings of the wide jaw plates, means upon the other end of the rivet for limiting the separatory movement of the first jaw and the first wide jaw plate, and an expansion spring encircling the rivet and interposed between the intermediate jaw plate and the first jaw.
